UNITED STATES PATENT OFFICE.

WILLIAM WATSON KENNEDY, OF CHICAGO, ILLINOIS.

PROCESS OF PROTECTIVE COLOR-PRINTING.

1,010,635.

Specification of Letters Patent.

Patented Dec. 5, 1911.

Application filed February 3, 1911. Serial No. 606,317.

To all whom it may concern:

Be it known that I, WILLIAM W. KENNEDY, a citizen of the United States, residing at Chicago, in the county of Cook and 5 State of Illinois, have invented certain new and useful Improvements in Processes of Protective Color-Printing, of which the following is a specification, reference being had therein to the accompanying drawing.

10 My invention relates to a new and improved process of color printing for producing tints by safety or protective anilin inks in printing bank notes, checks, and other instruments in which protection 15 against erasure or alteration is desired, and the invention consists in the matters hereinafter described and then pointed out in the appended claims. In protective printing for these various instruments, the paper 20 is provided with a tint produced by a plurality of fine lines or other impressions printed by safety inks which expose any erasure or alteration, the tint being of any 25 design or character, such for example as a pantograph tint, parallel or crossed lines etc., and being usually impressed or printed on the paper before the reading matter etc., is printed. In this protective printing as 30 practiced before my invention two methods were available for printing the tint or color on the paper; (1) the lithographic process involving the employment of a stone mounted on the horizontally reciprocating bed of a printing press and printing upon the 35 paper held upon the impression cylinder by suitable nippers or equivalent means; (2) the ordinary process of printing from a zinc plate on which the pattern is produced by making a large drawing thereof, then reducing the latter by photolithographic 40 reduction, stripping the reduced film from its plate, spreading the film on the zinc plate and "rolling-up" the lines which are protected with varnish ink from an acid bath, 45 the zinc plate then being mounted on a block of wood on the horizontally reciprocating bed of a press and printing directly upon the paper held on the impression cylinder by suitable nippers, and (3) the plate 50 process involving the employment of an ordinary metallic printing plate in a rotary press, in which process an impression is taken from a stone or engraved plate on thin paper by heavy ink not soluble in water 55 and is transferred to an ordinary plane-surface.

faced metallic printing-plate, the paper then being washed off the plate and the impression "rolled-up" with subsequent coatings of varnish ink, and the printing-plate is then mounted upon the revolving cylinder 60 of the press. In the first and second of these methods anilin protective inks may be employed to a limited extent only for reasons hereafter pointed out. The third or plate method requires inks that are not 65 soluble in water, such for example as those known in the trade as varnish inks, because it is necessary to dampen the "rolled-up" plate to prevent the printing ink adhering to its surface instead of only to the "rolled-up" impression and this damping would lower the affinity of the water-soluble anilin or water-color printing inks for the 70 printing lines of the impression and the printing ink would run into the minute depressions between the printing projections or lines of the "rolled-up" impression of heavy ink forming the printing surface or pattern and so smear or blur the tint impression. Furthermore, the "rolled-up" 75 printing plate method is incapable of printing with anilin or water-color protective inks under any conditions because the "rolled-up" impression of heavy ink forming the printing surface or pattern is so low 80 that the anilin or water-soluble inks, being more fluid and viscous than other printing inks, would run into the depressions and upon the surface of the plate itself and so blur the impression; this tendency is aggravated 85 by the character of the inking rollers which are leather covered which with either the smooth or grain or hair side out would wipe the viscous anilin inks into the depressions, 90 and upon the plate. For these reasons protective tint printing in anilin inks was limited before my invention to lithographic stone and zinc plate processes, and as the reciprocating presses upon which the stones and plates can be used have a capacity of 100 only about 5,000 impressions as compared with 30,000 to 40,000 impressions by the rotary presses for each working day of 8 or 9 hours each, the output of anilin ink protected work was restricted and confined to a 105 relatively small amount.

The limitations and restrictions imposed upon the use of anilin inks for protective tint printing by reason of the above facts, among others, are further objectionable from 110

the consideration that anilin inks are more desirable for such work than inks that are affected only by acids, etc., because after printing the tint the latter in time lose their protective quality as they become practically insoluble and unaffected by various agents employed in altering checks, etc., which may then remove the ink with which the superscription is written or printed 10 without affecting the tint and so permit the instrument to be altered. For this reason, among others, inks other than anilin do not provide tints of lasting protection, whereas anilin inks retain indefinitely their protective quality of solubility and neither water nor acids may remove the superscription without also affecting the tint and so exposing the fraud.

The object of my invention is to provide 20 a process whereby anilin protective inks may be employed for printing protective colors or tints from metallic plates upon rotary presses.

Some of the steps of the process are carried out upon a suitable rotary press having 25 certain modifications, and in the annexed drawing Figure 1 illustrates a practical form of press that may be employed for these steps; Fig. 2 is a top plan view of a check or other suitable instrument printed with a protective tint in accordance with my invention; Fig. 3 is a top plan view of a form of printing plate that may be employed, and Fig. 4 is a sectional view on an enlarged 35 scale on the line 4—4 of Fig. 3.

In the practice of my invention I print from the surface or material of the plate itself, and for this purpose I prepare a flexible metallic plate A in which the printing points of contact, representing the salients or top of the design or pattern, are fine and closely arranged and in high relief and raised above the body of the plate to a height much above that of ordinary "rolled-up" plates; in the latter the points of contact are usually less than one one-thousandth (1/1000) of an inch high, whereas in the plates employed in my process they are preferably eight times as high and in some 40 cases from fourteen to fifteen one-thousandths (14/1000 to 15/1000) of an inch high, the general proposition being true that the character of the work is improved as 45 the latter dimension is approximated. The 50 plate design, such for example as the crossed lines represented by the reference letter a, with other lines or points representing a border a' of any suitable design when the latter is desired, is prepared on a flexible 55 metallic printing plate. Where margins of the paper color are desired about the tint, as for example in bank checks, the material is etched or cut away at suitable places as 60 at a², and when vignettes, cuts, etc. are desired, it is either cut away at the desired 65

places for their insets or they may be produced in the material of the plate as at a³, as more fully hereinafter stated.

A suitably prepared plate A is secured in place upon a revolving cylinder B of an off-set press, the flexibility of the plate allowing it to accommodate itself to any suitable cylinder, and the plate is inked by the composition inking-rollers C applying the protective anilin or water-color ink thereto 70 from a suitable supply and driven in unison with the plate cylinder by suitable driving connections (not shown) to the main or drive shaft of the press. Hard-rubber rollers D are employed and revolved by any 75 suitable drive connections (not shown) in unison with and in contact with the top of the work of the plate A to smooth and equalize the ink upon the printing lines or points a of contact of the plate. A reversed impression of the design is transferred from the plate upon a transfer blanket or "set-off" E, usually a rubber blanket, mounted upon a suitably driven cylinder, and by the transfer blanket the impression of the design is made upon the sheets on the impression cylinder F which are fed through the machine in any suitable manner and as now well known in the art; it being understood that a set-off press is preferably employed.

In Fig. 2 I have shown a check tinted in accordance with my invention and it will be observed that the body of the check is covered by a tint produced by fine lines as a, that the border as a' is also of fine lines or impression points, that the margin as a² is clear in the color of the paper printed upon, and that the vignette as a³ may be varied to comprise any suitable matter, the same reference letters being employed as for the parts in the other figures producing these corresponding matters. The vignette or cut as at a³ may be produced in any suitable pattern or design in the metal of the plate 105 itself, and the tint of the body of the check may be any design as may the border, and the tint may of course be similarly applied to the check-coupon or stub.

By my invention finer work is possible for 110 providing the lines of the tint, including the borders, vignettes, cuts etc. than by the old processes.

In my invention the metal of the plate forms the printing surfaces and so they may 115 produce much finer and sharper lines or salients than with the lithographic stones or so-called zinc plates. In the stones the etching by the acid to produce the printing-surfaces is not under the operator's control and the 120 acid employed for that purpose will eat away the stone unevenly so that irregular lines are produced and the edges are undermined and broken so that they break down under the heavy pressure of "pulling" the 125 130

impression; this acid action also prevents fine-work such as vignettes, cuts of buildings, lathe-borders, or close impressions because it destroys the stone material between 5 adjacent cavities and so requires the intervening walls to be of considerable thickness with the result that the impression surfaces are widely separated and are broken and undermined. Furthermore, the cost of the 10 lithographic stones is so great, as only those of the highest quality free from veins and chalk spots can be used, that anilin ink protective printing is prohibited on ninety per cent. of orders requiring protective tints. 15 Also, the high cost of preparing the stones, the cost of ink consumed, and the limited number of impressions per day upon the reciprocating bed press render this process uncommercial and impractical; furthermore, 20 the pressure required to "pull" a clean even impression on the paper from contact with the printing surface of the stone is so great that soft papers are embossed and the stones wear quickly. 25 In the practice of my invention there is no pressure or embossing on the most delicate of papers and no wear on the plate, while the cost is no less than one-tenth of the lithographic process and the number of 30 impressions that can be taken in a day is increased five or six times. In the old zinc plate or second process above described only coarse work can be accomplished and it is not possible to print fine work for anilin 35 tinting of checks etc., by the zinc block; in fact this latter cannot produce any finer lines than the lithographic stones. For these reasons finer vignettes, building cuts, lathe borders, and tints all having finer and 40 sharper lines and contours can be printed in

anilin or water color inks by my process than by those of the prior art. Furthermore, my process provides for the production of margins in the color of the paper by merely etching or routing out the metal 45 of the plate between adjacent printing surfaces to such depth that no impression will be produced, the same being done where any special cut etc. is to be inset at any particular place. 50

Having described my invention, I claim:

1. The process of protective tint printing with anilin ink which consists in producing a flexible metallic printing plate having fine and closely arranged metallic printing surfaces in high relief above its face, inking the 55 surfaces with an anilin ink, spreading the ink to equalize it on the printing surfaces by a hard-rubber roller, and taking the impression upon the sheets. 60

2. The process of producing protective tints by printing with protective anilin ink which consists in producing a flexible metallic printing plate having fine and closely arranged metallic printing surfaces in high 65 relief above its face, rotating the plate with its printing surfaces in contact with an anilin ink-applying composition roller and in contact with a hard-rubber ink-spreading roller, transferring the impression from the 70 printing surfaces to a transfer surface or blanket, and taking the impression from the latter upon the sheets.

In testimony whereof, I affix my signature in presence of two witnesses.

WILLIAM WATSON KENNEDY.
